[57] CLAIM

The ornamental design for a CPR manikin, as shown and described.

DESCRIPTION

FIG. 1 is a front view of a CPR manikin showing our new design, the structure depicted by means of broken lines being shown for illustrative purposes only and forming no part of the claimed design;

FIG. 2 is a side view thereof, and with the opposite side thereof being identical thereto;

FIG. 3 is a rear view thereof;

FIG. 4 is a top plan view thereof; and,

FIG. 5 is a bottom plan view thereof.
